UNITED STATES PATENT OFFICE.

HUGH GRAHAM, OF DARTMOUTH, NOVA SCOTIA, CANADA.

CAR-COUPING.

SPECIFICATION forming part of Letters Patent No. 317,120, dated May 5, 1885.

Application filed September 1, 1884. (No model.)

To all whom it may concern:

Be it known that I, HUGH GRAHAM, of Dartmouth, Nova Scotia, Canada, have invented a new and Improved Car-Coupling, of which the following is a full, clear, and exact description.

The invention consists of the combinations of parts, substantially as hereinafter described and claimed.

10 Reference is to be had to the accompanying drawings, forming part of this specification, in which similar letters of reference indicate corresponding parts in both the figures.

Figure 1 is an end view of a car provided 15 with my improved car-coupling, the pin being raised. Fig. 2 is a longitudinal sectional elevation of the end parts of two cars provided with my improved coupling, one pin being raised and the other lowered.

20 The draw-head A, held on the under side of the car B in the usual manner, has the usual apertures.

The coupling-pin D has its lower end beveled or curved downward and toward the 25 rear, and a short distance above the said lower end the pin is provided in its front with an offset or shoulder, E, which is so located that when it rests on the draw-head the lower end of the pin will be a short distance 30 above the bottom of the draw-head, as shown.

From the pin D a rod, F, projects upward, the rod having its upper part squared or flattened, which upper part passes through a corresponding aperture in a guide-arm, G, 35 projecting from the end of the car near the top. The rod is thus prevented from turning, and the shoulder E will always be at the front of the draw-head.

The rod F extends to the top of the draw-

head, thus permitting of raising the coupling- 40 pin from the roof of the car.

A transverse shaft, H, journaled on the end of the car, is provided at each end with a handle, J, and has a middle arm, K, connected by a chain, L, with the top of the 45 coupling-pin D.

The pin D is provided with a head, D', to prevent it from dropping too far.

The operation is as follows: To set the 50 coupling, the pin D is raised and its shoulder E rested on the draw-head in front of the pin-aperture. When the entering link N strikes the lower beveled end of the pin, it forces it upward sufficiently to pass under it, and also 55 pushes it inward. When the end of the link has passed the pin, the latter drops and passes through the link, thus coupling the cars.

To uncouple, the pin D is raised from the 60 top of the car by means of the rod F, or from the sides of the car by means of the shaft H.

Having thus described my invention, I claim as new and desire to secure by Letters Patent—

1. In a car-coupling, the combination, with 65 the draw-head A, of the coupling-pin D, having a shoulder or offset, E, of the rod F, projecting upward from the pin and having its upper part squared, and of the guide-arm G, substantially as herein shown and described.

2. In a car-coupling, the combination, with 70 the draw-head A, of the coupling-pin D, the rod F, the arm G, the shaft H, the arm K, and the chain L, substantially as herein shown and described.

HUGH GRAHAM.
